ACTUATING MECHANISM FOR DOFFING MECHANISM

James Keith Anderson, Leeds, England

Application September 19, 1935, Serial No. 41,243
In Great Britain September 25, 1934

3 Claims. (Cl. 74—1)

This invention has reference to apparatus for imparting to two reciprocable members a predetermined sequence of movements. The invention is more particularly designed for use in the 5 operation of the doffing mechanism of spinning, twisting and like machines used in the production of yarns or threads. Machines of this type are old and well known. The doffing mechanism thereof usually includes lifter rails each having 10 a line of spindles thereon to receive bobbins. The doffing mechanism also includes elevating means actuatable by rocking movement of a shaft to raise a lifter rail into operating position wherein the bobbins carried thereon can receive 15 yarn from the flyers, and to lower the rail from such position when the bobbins have been filled. The doffing mechanism may also include rocking means actuatable by rocking movement of another shaft to shift a lifter rail forward and rearward 20 to facilitate the replacement of a lifter rail with full bobbins by a rail with empty bobbins in the manner described, for example, in my copending application Serial No. 747,692, filed October 10, 1934. According to the present invention, apparatus 25 is provided for imparting to said shafts suitable movements in a proper sequence for raising, lowering and shifting the lifter rails in a spinning machine.

Another object of the invention is to provide 30 interlocking mechanism by which spinning is prevented while the lifter rail is lowered, and lowering of the rail is prevented while spinning is in progress.

In the accompanying sheets of drawings which 35 are illustrative of my invention:—

Fig. 1 is an end elevation of sufficient of the framework of a machine to show the mounting thereon of my improved devices.

Fig. 2 is a plan of certain of the framework of 40 the machine showing my improved hand operated and other devices mounted thereon.

Fig. 3 is a similar end elevation to Fig. 1, the same being drawn to a smaller scale in order to show the application of my improved devices in 45 connection with the lifter mechanism.

Fig. 4 is a view of certain of the parts shown by Fig. 3 as seen from left to right of said figure.

Figs. 5 and 6 are side views showing the formation 50 of a separate cam surface on each side of a disc common to both.

The cam surface on one side of the disc is employed for one purpose and that on the other for another purpose, as is hereinafter explained.

A indicates a portion of the end frame of a 55 machine such as a spinning machine of the type

wherein traversing movement is imparted to the bobbins, relative to the flyers, to deposit yarn on the bobbins in orderly layers. The bobbins and lifter rails may be of any desired construction as well known in the art, and are not illustrated on the drawings. For raising and lowering the lifter rails, a chain 6 is paid out from and wound up on a drum 143, the motions of the chain being transmitted to the lifter rails by any suitable connecting mechanism which may include a rock 10 shaft 8 such as is illustrated in Figures 1 and 3. Mechanism for rocking the shaft 8 so as to impart traversing movement to the lifter rail is shown in Figure 3, such mechanism including a rotatable cam 2 which rocks a lever arm 3 connected by a 15 rod 3a to a bracket 4 secured by means of a bracket 12c to a lever 5 which is rockable on a shaft 5a journaled in a bearing 9 on the main frame A. The bracket 12c also carries a shaft 14c on which is mounted the rotatable drum 14b. 20 This drum is held against rotation during the spinning operation. From the drum 14b the chain 6 leads to a drum 7 on the shaft 8. Oscillation of the arm 3 by rotation of the cam 2 results in oscillation of the arm 5 and rocking 25 movements of the shaft 8 of sufficient amplitude to impart traversing movements to the bobbins (not shown). According to the invention, mechanism is provided for raising and lowering the lifter rails for doffing, without interfering with 30 the traversing mechanism.

The shaft 5a is arranged to have loosely mounted upon it a chain wheel 10, the chain 10a from which takes around another chain wheel 11 mounted loosely upon a fixed stud 11a that is 35 secured to the end frame A of the machine.

The chain wheel 11 which revolves loosely on the stud 11a is fixed to the hub of a hand wheel 11b (shown in broken lines) so that as said hand wheel is manually rotated, by the attendant, motion is transmitted to the chain wheel 10 by 40 means of the chain 10a.

Pivoted upon this chain wheel 10 is a pawl 10b which, by the actions of a spring, engages with the teeth of a ratchet wheel 10c that is keyed 45 upon the shaft 5a, so that a bevel wheel 10d (also fixed upon the shaft 5a) may mesh or gear with another bevel wheel 12 which is fixed upon so as to transmit motion to a shaft 12a carried by a bracket 12c fixed upon the lever 5, and the pivoted end 12b of said lever 5.

Mounted to slide upon the shaft 12a is a clutch coupling 13, the mounting of said coupling being such that the rotary motions transmitted thereto will be imparted to the shaft 12a while yet the 55

clutch member 13 may slide freely upon said shaft.

Adjacent to the clutch coupling 13 are mounted bevel wheels 13a and 13b which, while being loosely mounted upon the said shaft 12a, may derive their motion from said shaft 12a by the engagement of same with the clutch coupling 13 as is hereinafter explained.

The loosely mounted bevel wheels 13a and 13b are both made to gear with a bevel wheel 13c which is mounted upon a bracket supported by the lever 5.

On the hub of the wheel 13b is fixed a worm 14 which gears or meshes with a worm wheel 14a fixed upon so that it may thereby rotate the chain drum 14b.

The clutch coupling 13 which is splined upon the shaft 12a is arranged to be moved and retained in position by a fork lever 15 which is pivoted upon the frame A so that its lower end may be connected by a connecting rod 25b to a cam actuated lever 15b which is operated by cam and other mechanism as is hereinafter explained.

The cam lever 15b has its bowl 15c operated by a cam 15d (the cam surface 15w of which is shown by Fig. 6) mounted upon a shaft 16 which is pivoted at one end upon the end frame A and at the other end upon a bracket 16a. On this shaft 16 is also fixed another cam 17, the cam surface 17w (Fig. 5) of which is arranged to operate a bowl 17a pivoted on the upper end of a lever 17b which reaches for its lower end to be connected by a link 17c to a lever 18 which is fixed upon the oscillating shaft 18a upon which are mounted the lifter rail exchanging-members of the doffing motion of the machine (not shown), said lifter-rail-members being preferably of the type shown and described in the specification of my concurrent application for Letters Patent in the United States, Serial No. 747,692, so also are the order and mechanism and method of operating said members of the type explained in the same specification.

Although I herein refer to said doffing mechanism as being the doffing mechanism to which I apply my invention, it is obvious that I might make use of the same method of operating other devices by changing the character of the cam surfaces on the cams 15d and 17 hereinbefore described.

The rotary motions of the cam 17 are derived from the manually operated shaft 5a hereinbefore referred to, and this I effect by a bevel wheel 19 (fixed upon the shaft 5a) meshing with another bevel wheel 19a fixed upon the horizontal shaft 19b, in order that this horizontal shaft 19b may extend to have a worm 19c fixed upon it to mesh with a worm wheel 19d that is fixed upon so as to be able to rotate the cam 17 which is mounted loosely upon the shaft 16, and this cam 17 is the cam which operates the lever 17b hereinbefore described.

Fixed to and to the rear of the cam 17 is the other cam 15d which, as is stated, operates the lever 15b so as to actuate the clutch member 13 in manner hereinafter described.

In order to carry out the process of doffing by the operations of the mechanism hereinbefore described the attendant will rotate the hand wheel 11b in a clockwise direction. This movement of the wheel 11b will transmit motion through the chain wheel 11 and chain 10a to the wheel 10c, and this wheel 10c, by running loosely upon the shaft 5a, can only transmit motion to said shaft 5a in the direction stated, by reason of the pawl

10b which is pivoted upon the side of the wheel 10 engaging with the teeth of the ratchet wheel 10c fixed upon the shaft 5a. Consequently, anyone rotating the hand wheel 11b in the opposite direction to that stated will have no effect on any of the mechanism for carrying out the process of doffing, since the pawl 10b will slide freely over the teeth of the ratchet wheel 10c.

The motions of the shaft 5a are transmitted (through the bevel wheel 10d fixed thereon) to the bevel wheel 12, so that this bevel wheel 12 will rotate the shaft 12a.

The motions of the shaft 12a will then be transmitted in such a direction as the clutch member 13 may effect under the control of the cam 15d as is hereinbefore explained. The drum 14b is thus driven by the shaft 12a in one direction or the other, or is idle, according to the position of the clutch member 13 as determined by the cam 15w. The shaft 18a is rocked directly through actuation of the bowl 17a by the cam 17w. By suitably shaping the cams 15w and 17w, various combinations and sequences of rocking movements of the shafts 8 and 18a can be had. For example, these shafts may be so rocked as to carry out the proper sequence of movements of carrier for raising and lowering the lifter rails and the mechanism for shifting lowered lifter rails forward and rearward, incidental to doffing operations. Thus, the worm 14 may be rotated in a direction to cause the drum 14b to pay out the lifter chain 6, which is normally coiled thereon, to lower the bobbin supporting rails in the spinning machine, and such lowering will continue until the clutch member is again removed from transmitting motion from the shaft 12a when the lifter rail will have passed below the members of the well known doffing apparatus and will have received the rails carried by the full bobbins that have been discharged from the spindles, and said rails will remain in said position upon the supporting members of the machine until other actions take place as follows.

In the position stated the cam 15w will have carried the bowl 15c from the position shown in broken lines Fig. 6 to a position where the part of the cam surfaces C' of said cam will have moved said bowl in order to cause the clutch member 13 to be brought centrally between the clutch teeth of the bevel wheels 13a and 13b where the motions of the shaft 12a will cease to transmit motion to said wheels and therefore to the worm 14.

During the rotary motions of the hand wheel as above described and for transmitting motion to the shaft 5a as stated, the shaft 5a will have transmitted motion through the bevel wheel 19 to the bevel wheel 19a which is fixed upon the shaft 19b, and therefore said shaft 19b will have transmitted motion through the worm 19c and worm wheel 19d and the cams 15d and 17.

As is stated, during such motion the cam 15d will have moved the clutch member 13 to its idle position. At the same time motion of the cam 17 will have brought the cam surface D of said cam away from supporting the bowl 17a which it operates, so that same will have operated the lever 17b to rock the shaft 18a and thereby to shift the receiving members for the lifter rails in the spinning frame to receive said rails and their full bobbins as is hereinbefore described. Immediately after thus receiving said bobbins the part D' of the cam surface of the cam 17 will be operating the bowl 17a to carry the lever from its extreme position shown in Fig. 1 to the opposite

position where it will adjust the lifter rail supporting members in their most forward positions at the front of the machine where they will retain said lifter rails and their full bobbins. And 5 simultaneously with said adjustment the said movements will have also brought forward other lifting rails for the spinning machine provided with empty bobbins so that same are brought into position for their operating and traversing members belonging to the traversing members of the 10 spinning machine to raise said empty bobbins and their spindles into the spinning positions.

The lifting or raising of the bobbin supporting rails as described is carried out by reason of the 15 cam 15d having brought its cam surfaces C¹ to act upon the bowl 15c in order to cause the shaft 12a to revolve in the opposite direction to that indicated by the arrows G shown in Figs. 5 and 20 6, and these rotations of the shaft 12a will cause the drum 14b to raise the lifter rails and their bobbins back to their operating positions herein-before described.

In order to avoid the possibility of accidental 25 operation of the cam wheels 15d and 17, and the mechanism driven or controlled thereby, during a spinning operation, I provide interlocking devices as illustrated in Figures 3 and 4. The drive of the spinning mechanism is controlled through a starting lever H which moves 30 an idle pulley 40 to tighten a loose belt 41 by which power may be transmitted to drive the spinning mechanism. When the lever H is raised, the belt is loose and the spinning mechanism is not driven. The lever H may be locked in its 35 elevated position by a lug 32 mounted on a rocking lever 31 which is pivoted at 31a and which carries at its other end another locking lug 30 adapted to enter notches K and K' in the periphery of the disks 15d and 17. When either of 40 these notches is opposite the lug 30, the lever 31 may be rocked by the handle 33 to move the lug 30 into a notch, at the same time releasing the lever H which can then be depressed to start the spinning. As indicated in Figure 3, the 45 depressed lever H is in the path of the lug 32 so that the lever 33 cannot be rocked to release the cam wheel while spinning is in progress.

On reaching this position the starting handle H of the driving mechanism of the machine may 50 be moved into its position shown in full lines Fig. 3 so that the spinning operations commence and the threads which extend from the full bobbins (situated at the front of the machine as before stated) will be paid out from said bobbins and 55 for a certain number of revolutions of the flyers will be wound upon the empty bobbins situated to receive same, and when the desired number of coils have been thus put upon the empty bobbins the thread extending from the full bobbins would 60 be severed by the attendant who may then allow the spinning frame to continue its motions, while the cams 15d and 17 still remain in such positions as to allow the sets of lifter rails having the full bobbins to have same removed and empty 65 bobbins substituted for said full bobbins thereof, after which the attendant may then move the hand wheel 11b and so cause the cams 15d and 17 to re-adjust the supporting members for the lifter rails to the rearmost positions in the 70 machine, and, when the lifter mechanism is so adjusted, said rails will remain ready for the next doffing operation to be performed.

As means for preventing the doffing mechanism of the spinning frame being interfered with 75 during the effective motions of the said spin-

ning frame, a sliding locking stud 30 (Figs. 3 and 4) is fixed upon a vertical lever 31 pivoted at 31a on a bracket fixed to the end frame A, so that a projecting member 32 fixed on the lower end of the lever 31 may be retained clear 5 of the starting lever H and remains there during all effective operations of the spinning machine. However, by said projections 32 remaining opposite the body part of the lever H, during 10 said operations of the machine it prevents the lever 31 from being moved by the handle 33, and therefore said lever will retain the locking stud 30 within the notch K or K' formed in the peripheries of the cams 15d and 17. Hence, during 15 the motions of the machine the attendant cannot actuate the hand wheel 11b in the right direction for moving any part of the doffing engaging mechanism described.

When the attendant desires to carry out the process of doffing the starting handle H is raised 20 so that the projection 32 may be placed below said starting handle H as is shown by Fig. 3. Thus the cams 15d and 17 will be liberated when the handle 33 is pushed and the hand starting lever will be locked so that the starting of the 25 machine into action during the operating of the mechanism for carrying out the process of doffing, is prevented.

The notches K and K' in the cams 15d and 17 30 are to enable the attendant to place the locking stud 30 in the notch K to lock the doffing motion against being actuated by the attendant, and simultaneously to remove the projection 32 from interfering with the free movements of the starting handle H. The attendant may then operate 35 the handle H and start the machine into spinning action to wind the threads on to the empty bobbin where they are then cut to sever them from the full bobbins in known manner. The spinning operations may then proceed for a 40 period as desired, and the attendant, during such operations, will be enabled to remove the full bobbins and substitute the empty bobbins as above described, after which the attendant will 45 then operate the handle H and arrest the motions of the machine so that he may then, by the handle 33, disengage the doffing motion to permit the attendant again to operate the hand wheel 11b and complete the full doffing operations by moving the cams 15d and 17 back to 50 their initial positions where he may then again operate the handle 33 and lock the cams 15d and 17 by placing the locking stud 30 in the notch K', after which he may start the machine into 55 action and complete the spinning operations.

Such being the nature and object of my invention, what I claim is:—

1. In a machine of the kind described having power driven mechanism, a starting lever for controlling the drive of said mechanism, and two reciprocable members; apparatus for imparting movements to said members in a predetermined sequence, and means for interlocking said starting lever and apparatus so that when either is operative the other is locked against 60 operation.

2. In a machine of the kind described having power driven mechanism, a starting lever for controlling the drive of said mechanisms, and two reciprocable members; apparatus for imparting movements to said members in a predetermined sequence, and means for interlocking said starting lever and apparatus so that when either is operative the other is locked against 70 operation, said apparatus comprising a driving 75

- element, a cam wheel with two cams thereon driven by said element, cam followers for said respective cams, means operably connecting one of said members to one of said followers to be actuated by movements thereof, means including a reversing gear connecting said driving element to the other said member, and means actuated by the other said cam follower to control said reversing gear, said interlocking means including a lug movable into engagement with said cam wheel to prevent movement thereof.
3. Apparatus for operating a pair of reciprocable members of a doffing mechanism for spinning machines or the like, comprising a frame, a shaft bearing fixed on said frame, a shaft journaled in said bearing, means actuatable to rotate said shaft, a rotatable cam member having two cams thereon, driving connections between said
- 5
